Primary Examiner — Jennifer Rivard*Assistant Examiner* — Catherine S Posthauer(74) Attorney, Agent, or Firm — Cantor Colburn LLP(57) CLAIM

We claim, the ornamental design for a grill, as shown and described.

DESCRIPTION

FIG. 1 is a perspective view of a grill, showing our new design;

FIG. 2 is a front view thereof;

FIG. 3 is a rear view thereof;

FIG. 4 is a side view thereof, taken from the left of FIG. 2;

FIG. 5 is a side view thereof, taken from the right of FIG. 2;

FIG. 6 is a top plan view thereof; and,

FIG. 7 is a bottom plan view thereof.

The dot-dash lines represent the boundaries of the claim, and form no part thereof.

1 Claim, 5 Drawing Sheets(56)
